MOTOR CONTROL SYSTEM

Charles A. H. Watson, Highland Park, and Fred E. McKinster, Detroit, Mich., assignors to McCord Radiator & Mfg. Co., Detroit, Mich., a corporation of Maine

Application March 2, 1934, Serial No. 713,660

2 Claims. (Cl. 172—288)

This invention relates to electrically operated driers of the type which discharge a continuous blast of heated air for hand, face, hair, apparel and other drying purposes.

5 An objection to devices of this character as heretofore used is that a blast of relatively cool air is discharged from the drier on each starting operation. This is due to the fact that the blowers in these driers are operated at high speeds 10 and at full air volume at all times and the electrical heating element for heating the air is unable to raise the temperature of the high velocity air to the hot blast required for drying purposes until the blower has been in operation 15 for an appreciable length of time.

The general purpose and object of our invention is to overcome this objection and we do so by so constructing the drier as to reduce the velocity of the air for a short period of time 20 on starting the drier so that the heating element may rapidly raise the temperature of the low velocity air to that required for drying purposes. Thus the drying action is not delayed as heretofore, for the initial blast is quickly brought 25 to the temperature range of the hot blast produced by the continued operation of the blower.

To accomplish this result, we provide means in the drier assembly acting automatically on each starting of the blower to reduce the blower 30 speed for a short period of time, say ten or twenty seconds, so that the heater may quickly raise the temperature of the slow velocity air, after which the blower is allowed to resume its normal high speed and full air supply. In practice, the motors which rotate these blowers have a top or normally high speed of approximately 3500 R. P. M. In accordance with our invention, we reduce this speed considerably on each starting operation, for example, between 500 and 1000 35 R. P. M. for the desired period of time to obtain rapid heating of the low velocity air.

In carrying out the objects of our invention we control the speed of the motor by providing a resistance in the motor circuit, said resistance 40 remaining in the circuit for the period of time desired and automatically cut out after that time so that the motor may resume its normal high speed.

A further object of our invention is to control 45 the cutting in and out of the resistance by the use of a timing element or mechanism automatically brought into and out of operation in the starting and stopping of the blower.

Other and further objects of our invention will 50 appear from the following specification taken in

connection with the accompanying drawings, in which:

Fig. 1 is a side view of a drier assembly embodying the features of our invention;

Fig. 2 is a top plan view of the parts shown 5 in Fig. 1;

Fig. 3 is a vertical sectional view with parts in elevation taken on line 3—3 of Fig. 2;

Fig. 4 is a perspective view with parts broken away and in section, respectively, of the actuating lever of the starting switch for the drier;

Fig. 5 is the wiring diagram; and

Fig. 6 is a front view of the drier device on a pedestal support.

Drier devices of the character to which our 15 invention is applicable have, as shown in Figs. 1 and 2, a centrifugal blower 1, an electric motor 2 for rotating the fan or air impeller 3 of the blower, and an electrical heating element 4 for heating the air discharged from the blower. 20 These elements are usually arranged in horizontal alignment, the blower 1 being between the motor and the heating elements 2 and 4, respectively. The blower has an air discharge nozzle 1a extending outwardly from the front side 25 of its casing as shown in Fig. 6. The outer end of the nozzle is usually covered by a protective screen 1b as shown. The heating element 4 is usually located in part at least in a tubular housing 5 on the air intake side of the blower 30 and secured to and extending laterally outward therefrom as shown in Figs. 1 and 2. The outer end of this housing is open and provides the air intake opening for the blower. The heating element comprises a coil of electrical resistance 35 wire 4a arranged in spiral form about a suitable spider or support 4b of insulating material. The ends of the wire are connected to terminals 6, 7 on the housing 5 whereby the heating element may be connected with the current supply in the 40 manner to be presently described.

The supply of electric current to the motor and the heating elements 2 and 4 is controlled by a switch 8 mounted on the base plate or support 22 for the drier assembly. The switch 8 45 is of the double pole type having upright fixed contact posts 9, 10 arranged in pairs on opposite sides of an actuating lever having an outer member 11 and an inner member 12. These members straddle an upright standard 13 and the inner 50 member 12 is pivoted intermediate its ends to the standard at 14 as shown in Fig. 3. The members 11 and 12 are approximately equal in length and the outer member 11 has its inner ends notched and engaging a fulcrum pin 15 55

carried at the adjacent end of the inner member 12 as shown in Fig. 4. A yoke 16 connects the main operating rod 17 of the drier device with the pin 15. The rod 17 is located in the pedestal support 18 for the drier and is pivoted at its lower end to a foot pedal 19 adjacent the lower end of the pedestal as shown in Fig. 6. In operating the drier the user presses downwardly on the pedal 19, thereby raising the rod 17 and closing the switch 8 in a manner to be presently described. A spring 20 associated with the pedal raises the pedal and lowers the rod 17 to open the switch 8 when the pedal is released.

The standard 13 is secured to the base plate 21 of the switch 8. This base plate, which is of insulating material, has an opening 21a therein whereby the arm 16a of the yoke 16 may extend through the plate for pivotal connection with the upper end of the rod 17. The upper end of the rod 17 is bent, as shown in dotted lines in Fig. 1, to reach the arm of the yoke when the switch 8 is in offset relation to the pedestal 18 as shown in the drawings. The base plate 22 for the drier assembly is also apertured to receive the arm of the yoke. Plate 22 in the pedestal type of device is secured to the upper end of the pedestal to support the drier assembly thereon.

The movable contacts of the switch 8 are in the form of strips or plates 23, 23 arranged on opposite sides of the actuating lever and disposed to bridge the upper ends of the contact posts 9, 10 when the switch is closed as shown in Figs. 1 and 2. These strips or plates 23 are carried by a movable support 24 in the form of a plate of insulating material, said plate being disposed above the standard 13 and pivotally connected thereto by member 25. This member is in the form of a yoke straddling the standard 26 and is fulcrumed on the standard at 26 as shown in Fig. 3. This pivotal mounting is disposed on the outer side of the fulcrum 14 for the actuating lever and preferably slightly below the same. The contact plates 23, 23 are yieldably supported by springs 27, 27.

The members 11, 12 of the actuating lever for the switch move in unison when opening and closing the switch 8. For ease of operation in opening the switch, the inner member 12 moves slightly in advance of the outer member 11 in the initial operation of the lever. Thereafter the members are connected together by the outer end of the member 12 engaging under a flange or ledge 28 at the outer end of the member 11 as shown in Fig. 4. A pair of coiled springs 29, 29 are employed for giving a quick snap opening and closing movement to the switch in its operation. These springs are located on opposite sides of the actuating lever and have their outer ends connected thereto by a pin 30. The inner ends of the springs are connected to the movable plate 24 of the switch through depending members 31, 31 thereon. These members may be integrally connected by being formed from a single piece of metal bent to U-form, as shown. This member is located on the plate 24 in inward spaced relation to the fulcrum 14 for the actuating lever. The parts are so constructed and arranged that the springs 29 as they pass the pivotal points 14 and 20 will impart a quick snap motion to the switch, drawing the contact plates 23, 23 into engagement with the posts 9, 10 when closing the switch and moving these plates out of contact with said posts on opening the switch.

Arranged on the base plate 22 opposite the switch 8 is a timing mechanism 32. This mechanism comprises a pair of laterally spaced upright plates or standards 33, 33 forming a support for a speed reducing gear train of the type usually employed in clock work. Secured to one terminal shaft 34 of this gear train is a disc 35 of electrical insulating material. This disc rotates with the shaft 34 and is provided with an arm 36 which has movement exterior of the plates 33 as shown in Fig. 3. An electrical contact element in the form of a roller 37, is mounted on the outer end of the arm 36 for making contact with a pair of upright contact fingers 38, 38 secured to the base 32a of the timing device. This base is of insulating material and the fingers 38 are connected in the motor circuit as hereinafter described.

Movement of the roller 37 into and out of contact with the fingers 38 is created by a pair of contracting coiled springs 39, 40 connected respectively to the opposite ends of a lever 41 fulcrumed intermediate its ends at 42 on an upright standard 43 secured to the base plate 22 of the drier assembly. Links 44, 45 connect these springs with the disc 35 on opposite sides of the shaft 34 and in substantially equal radial distances therefrom. The disc has pins 46, 47 for connection with the links, the latter being preferably in the form of rigid wires having their ends looped about the pins as shown. The opposite ends of the wires have a looped connection with the adjacent springs 39, 40. The lever 41 is provided with a co-planar arm 48 extending radially outward from the lever on its side opposite the springs. This arm is long enough to reach the inner end of the switch actuating lever 11-12 and engages the inner member 12 thereon in an ear 49 as shown.

When the actuating lever of the switch 8 is moved to close said switch, the inner end of the lever is moved upwardly as shown in Fig. 1. This swings the lever 41 about its fulcrum 42 and moves the upper end of the lever to the right and the lower end to the left when the parts are viewed as in the drawings. In this movement the lower spring 40 is expanded and through its link 45 rotates the disc 35 in a direction to lower its contact member 37 into engagement with the fingers 38. The speed of rotation of the disc is controlled however by the gear reduction of the timing mechanism 32 and also by a governor device 50. This governor is preferably in the form of a bladed member secured to the terminal shaft 51 of the gear reduction opposite the disc 35 and its speed of rotation is controlled by the resistance offered to the movement of its blades by contact with the surrounding air. In the device shown the speed is such that it takes approximately 10 seconds for the arm 36 of the disc 35 to move from its uppermost position in Fig. 3 to its lowermost position in contact with the fingers 38. This time may be varied by changing the size of governor blades. The upper spring 39 of the lever 41 is fully contracted at this time and does not interfere with the downward movement of the arm.

When the actuating lever of the switch 8 is moved to open the switch, the inner end of said lever is lowered, carrying therewith the arm 48 of the lever 41 as shown in Fig. 3. This rocks the lever 41 in a direction reverse to that above described, expanding the upper spring 39 and 75

rotating the disc 35 to raise its arm 36 out of contact with the fingers 38. The speed at which the arm 36 moves upwardly is controlled by the gear reduction and its governor 50. The lower 5 spring 40 contracts and does not interfere with this movement. A stop 52 may be provided to limit the upward movement of the arm 36 as indicated in Fig. 3. With the links 44, 45 in crossing relation, as shown, the lower spring is connected with the upper portion of the disc 35 and the upper spring is connected with the lower portion of the disc, thereby causing rotation of the disc in opposite directions on rocking the lever 41 as described.

15 Arranged in the motor circuit is a resistance 53 having a number of outlets 54 whereby the resistance desired may be obtained by connecting the wiring to the selected outlets. In the drawings, we have shown the full resistance employed in the motor circuit. The supply wires 55, 56 are connected with the terminals 9a, 10a of the forward set of posts 9, 10 of the switch 8. Two sets of wires are connected to the terminals 9b, 10b of the rear set of posts 9, 10. The 20 wires 57, 58 of one set connect these terminals with the wires of the heating element 4. As to the wires 59, 60 of the other set, the wire 59 leads directly to one of the terminals of the motor 2 as shown in Fig. 2. The wire 60 leads to one 25 of the terminals 54 of the resistor 53 as shown in Fig. 2. A wire 61 connects this terminal to one of the spring contact fingers 38 as also shown in Fig. 1. A wire 62 connects the other spring finger 38 to one of the other of the terminals 54 of the resistance 53 and this terminal by a wire 63 is connected to the other terminal of the motor 2.

30 The wiring diagram is illustrated in Fig. 5. By referring to this diagram, it will be clear that 40 when the switch 8 is closed and the contact member 37 of the timing mechanism is out of engagement with the fingers 38, the flow of current to the motor will be through the resistance 53. Thus the speed of the motor will be reduced and the amount or volume of air drawn into the blower will be less than when the motor is operating at full current supply. When the contact 45 37 is moved into engagement with the fingers 38, the resistance in the motor circuit will be cut out and the motor will operate it at full or normally high speed. The heating element 4 receives its full current supply whether the resistance is in or out of the motor circuit. This 50 is due to the fact that the heating element is connected with the current supply in advance of the switch 37-38.

55 The operation of the mechanism shown and described has already been given in connection 60 with the description of the various parts of the mechanism. It will be unnecessary therefore to again describe the operation in detail. Briefly, with the resistance 53 in the motor circuit on starting the drier, the speed of rotation of the motor will be reduced and the amount of air drawn into the blower will be less than when the blower is operated at its full or normal high speed. At the reduced air supply, the heating element 4 may quickly raise the temperature of the low velocity air so that a hot blast will be discharged from the blower almost immediately on starting it or within a very short time thereafter. This time element is controlled by the timing device 32 and as heretofore stated, closes 65 the switch 37-38 within approximately ten sec-

onds after the motor has been started. By this time a hot blast is being discharged from the blower, and the motor is rotated at its normal high speed by cutting the resistance 53 out of the motor current. The foot pedal 19 must be 5 held depressed to keep the blower in operation. On releasing the pedal, both switches are opened and the timing mechanism 32 is automatically restored to its starting position to place the resistance 53 in the motor circuit. The resistance 10 used will be of the type whereby the motor speed may be reduced to the speed desired, as within the example heretofore given.

15 The disc 35 may be given irregular shape, as shown in the drawings, to avoid interference with the adjacent shaft in the gear train. The drier assembly is housed within a cover 64 at the upper end of the pedestal 18. The discharge nozzle 1a of the blower extends outwardly through a vertical slot in this cover, the blower 20 being adjustable above the axis of the motor for raising and lowering the nozzle to suit the convenience of the user of the device.

25 The details of construction and arrangement of parts shown and described may be variously changed and modified without departing from the spirit and scope of our invention except as pointed out in the appended claims.

30 It is to be understood that we do not limit ourselves to the particular form of switch disclosed for actuating the device for controlling the speed of the motor as said device may be operated by other mechanical means, such as a control push rod. Moreover, it is within the 35 contemplation of our invention to vary the period of the timing action of the said motor control device by employing springs of different tensions or adjustable means for the springs or the links for adjusting the spring tension.

40 We claim as our invention:

1. In combination, an electric motor, a circuit for the motor, a main switch and a resistance in the motor circuit for respectively starting and stopping the motor and reducing the speed of rotation thereof, a shunt circuit for the resistance, 45 a supplemental switch in the shunt circuit for cutting the resistance in and out of the motor circuit, a timing device for retarding the opening and closing of the supplemental switch, said supplemental switch having separable contacts, one in the shunt circuit and the other carried by a revolute member in the timing device, a lever pivoted intermediate its ends and connected with the main switch for actuation thereby, and 50 means including tension springs connecting the opposite ends of the lever with the revolute member for opening and closing the supplemental switch in response to the opening and closing movement of the main switch.

60 2. In combination, an electric motor, a circuit for the motor, a main switch and a resistance in the motor circuit for respectively starting and stopping the motor and reducing the speed of rotation thereof, a shunt circuit for 65 the resistance, a supplemental switch in the shunt circuit for cutting the resistance in and out of the motor circuit, a timing device for retarding the opening and closing of the supplemental switch, said supplemental switch having separable contacts, one in the shunt circuit and the other carried by a revolute element in the timing device, a lever fulcrumed between the timing device and the main switch and having a pair of arms movable in union and arranged 70 75

in right angular relation to each other, one arm of said lever extending toward the main switch and connected therewith for actuation thereby in opening and closing said main switch, the other arm of the lever extending on opposite sides of the first mentioned arm, and links arranged in crossing relation and connecting the opposite ends of the second mentioned arm with the ro-

tatable element of the timing device on opposite sides of its axis of rotation, said links including contractile springs adapted to be respectively expanded in the movement of the lever in opposite directions by the main switch to effect rotation of the revolute element.

CHARLES A. H. WATSON.
FRED E. MCKINSTEE.
